FIG. 2.

UNITED STATES PATENT OFFICE

GEORGE OTTO KUNICKE, OF DUNELLEN, NEW JERSEY

AEROPLANE

Application filed July 12, 1929. Serial No. 377,861.

This invention relates to aeroplanes.

It is among the objects of the present invention to provide a novel and improved aeroplane of simple and efficient construction and well designed to meet the demands of economic manufacture.

It is a further object of the present invention to provide an aeroplane with novel and improved means for propelling the same.

It is a further object of the present invention to provide an aeroplane including propelling means which act to retard the downward movement of the aeroplane in a nose dive.

It is a further object of the present invention to provide an aeroplane having a longitudinally-extending passageway, together with means for closing the rear end of the passageway so that the same will act as a parachute to retard the downward movement of the plane.

Other objects and features of the present invention include the novel combination and interrelation of the parts whereby the whole provides a simple and improved construction.

Other objects of the present invention will be apparent from a consideration of the following specification taken in conjunction with the accompanying drawings, in which

Figure 1 is a top plan view of one form of the present invention, with portions broken away;

Fig. 2 is a side elevation with the motor portion and door portion in section;

Fig. 3 is a front elevation of the device, and

Fig. 4 is a detail view of the door portion with the closure portions therefor in closed position.

Referring more particularly to the drawings, the invention includes the conventional longitudinally-extending fuselage indicated by the numeral 10, together with the transversely-extending front wing 11. The fuselage 10 preferably includes the usual windows 12 and the pilot seat and operating assembly generally indicated at 14. The fuselage further includes at the tail end, the rudder 15, and is, in the present form of the invention, supported by the wheel assembly indicated by the numeral 16. It will be understood that the

invention is not confined to the specific type of fuselage herein indicated and that the invention is applicable to various forms of both land and water crafts of either monoplane or biplane construction.

Associated with the fuselage rear of the driving compartment, there is provided a pair of parallel longitudinally-extending air passageways 17, preferably formed by suitable housings 18 secured to the fuselage 10. The outer side walls of the housings 18 are parallel to the axis of the plane, whereby air passing therethrough will have a direct free straight path through the passageway. The upper and lower walls of the passageways are tapered to conform with the usual streamline taper of the fuselage 10. The housings 18 are open at the front, as at 19, and at the rear, as at 20, whereby the construction provides a funnel-like passageway larger at its forward end and decreasing in cross section at its rearward end, but being of substantially uniform width throughout.

For propelling the craft, there is mounted in each of the passageways 17, motor and propeller assemblies, indicated at 21, and suitably controlled by the pilot, as at 14, whereby with the motor and propellers running, air will be drawn in through the forward open end 19 of the passageway and will be expelled through the rearward end 20. This construction provides a double efficiency for the propellers in that they not only pull the craft forwardly at the propeller, but the exhaust of the air at 20, due to the contour of the passageways, will further push the craft forwardly, thus increasing the efficiency of the propellers.

The invention is, however, not confined to the use of the propellers within the housings 18, but it will be readily seen that the driving propellers may be mounted in other locations, if desired. It will be seen that regardless of the mounting of the propellers, the speed of the plane will act to cause a rapid passage of air through the passageways 17.

In case of emergency, such as an uncontrolled nose dive, it is desirable to provide means for retarding the movement of the plane through the air. This is accomplished

in the present invention by means of upper and lower pivoted closures 22 and 23, respectively. The upper closure 22 normally lies adjacent the upper wall of the passageway, while the lower closure 23 is adapted in normal position to form the lower end wall of the passageway. The closures 22 and 23 are pivotally associated with the walls as at 24, to swing on horizontal axes and are pivotally movable by a pair of interengaging arms 25 associated with the lower closure and 26 associated with the upper closure. The pin 10 of the lower closure extends transversely to provide an operating link 27 which passes through the fuselage and which is provided within the fuselage with an operating lever 28 connected in suitable manner as by a cable 29, to a controlling pulley 30 mounted within the operator's compartment. The arrangement 15 is such that when the cable 29 is wound about the pulley 30, the lever 28 is rocked in counterclockwise direction, thus raising the lower closure 23, and, at the same time, rocking in counterclockwise direction the arm 25, which by such rocking engages the arm 26 of the upper closure 22, thus causing the closure 22 to be moved downwardly with the upward movement of the closure 23, whereby the two co-operate to close or partially close the rear end 20 of the passageway 17.

From the foregoing it will readily be seen that in the operation should the plane go into an uncontrolled nose dive or if it should be desired for any reason to retard the movement of the plane, the cable 29 may be wound upon the reel 30, thus closing or partially closing the rear end of the passageway 17, whereby the passage of air therethrough will be retarded and the speed of the plane will be materially cut down. It will be seen that in a nose dive, the passageways 17 with their rear ends closed, act virtually as parachutes in preventing the rapid descent of the craft.

From the foregoing it will readily be seen that the invention provides novel and improved construction which will materially increase the factor of safety of aircrafts.

It will be understood that the invention is not confined to the specific structural details herein enumerated and that numerous changes, modifications and the full use of equivalents may be resorted to without departing from the spirit or scope of the present invention as outlined in the appended claims.

What is claimed is:

1. In an aeroplane, the combination with a fuselage and wing assembly, of a pair of longitudinally extending passageways parallel with the fuselage and formed by housings mounted on the fuselage, said passageways being of uniform width and diminishing height toward their rear, and motor and propeller assemblies mounted in the forward

end of said passageways, the passage of air through said passageways being controlled by closure members for said passageways, said closure members being pivotally mounted in the rear end of the related passageway, 70 said closure members being arranged for cooperative movement in response to control by the pilot, said closure members having angularly associated interengaging members, whereby movement of one of said closure members will cause movement of the other closure member.

2. In an aeroplane, the combination with a fuselage and wing assembly, of a pair of longitudinally-extending passageways parallel with the fuselage and formed by housings mounted on the fuselage, said passageways being of uniform width and diminishing height toward their rear, and motor propeller assemblies mounted in the forward end, 80 of said passageways, the passage of air through said passageways being controlled by closure members for said passageways, said closure members being pivotally mounted in the rear end of the related passageway, 85 said closure members being arranged for cooperative movement, common means connected with one of the closure members of each passageway to operate them in unison, and coacting means on the closure members 90 of each passageway causing one to move in response to the other.

GEORGE OTTO KUNICKE.
